MATTRESS

Robert H. Hamblin, Worcester, Mass.

Application December 6, 1938, Serial No. 244,225

3 Claims. (Cl. 5—191)

The present invention relates to a mattress construction, with particular reference to a device especially constructed for hot weather so that the occupant may be comfortable regardless of the atmospheric temperature.

Sleep, in hot weather, is made uncomfortable or impossible with the usual mattress made up entirely of a fibrous padding, or made up of a pad overlying springs, since no cooling air can circulate through the mattress to cool the occupant, and since the heat of the body is in no way conducted away from the occupant, as the pad forms a heat insulating element. In this way the large part of a person's body in contact with the mattress is not available for radiation of heat or evaporation of perspiration. The principal object of the present invention is the provision of a mattress construction which will provide for a circulation of air underneath the occupant, and which will also provide for conducting heat away from the occupant.

Inner spring mattresses which have a pad laid over a large number of coil springs, all built into a single unit, are frequently provided with small openings in the side walls to provide for the intake and discharge of air resulting from the compression of the mattress by a user. But such openings, although they allow the passage of air through the mattress, do not provide any cooling action on the occupant of the mattress since there still exists a relatively thick insulating pad between the air and the occupant of the mattress. A further feature of the present invention is to allow for a circulation of air directly in contact with the occupant of the mattress.

Other and further objects and advantages of the invention will hereinafter appear from the following detailed description taken in connection with the accompanying drawings, in which—

40 Fig. 1 is a plan view of a mattress embodying the invention, with parts broken away.

Fig. 2 is a fragmentary sectional view along the line 2—2 of Fig. 1.

Fig. 3 is a plan view on a greatly enlarged scale of a small section of the top of the mattress.

Fig. 4 is a sectional view along the line 4—4 of Fig. 3.

Fig. 5 is a sectional view similar to Fig. 2, showing a modification.

50 Fig. 6 is a sectional view similar to Fig. 2, showing a further modification.

With reference first to Fig. 1, the mattress has a base 1 in the form of a grid having a plurality of uniformly spaced bars 2 secured at opposite ends to a rectangular element 3. On the

base member are positioned a large number of uniformly spaced springs 4 which are vertically compressible, the springs in the construction shown being a conventional type of coil spring. Suitable clips 5 hold the springs securely to the base member.

The top member 5 for the mattress is made up of interwoven strips 6 of relatively thin narrow material which is preferably, although not necessarily, a conductor of heat. These strips are spaced apart preferably a distance approximately equal to the width of the strips, as best shown in Figs. 1 and 3, and the strips are held in spaced relation to each other by suitable permanent attachment along the edges of the top member, as by means of rivets 7, Fig. 2.

Both the longitudinal and lateral strips 6 are bent at spaced points to form depending loops 8. The loops are in line with each other, as shown, both laterally and longitudinally, and as a result, the top member, as shown in Fig. 2, is made up of a plurality of relatively small rectangles 9, one of which rests on the top of each spring, and which are held resiliently in predetermined spaced relation to each other by the resilient loops 8. Thus, when the mattress is occupied, the relatively small rectangular portions can bend relative to each other and can move so that the top surface of the mattress will accommodate itself to the contours of the user's body. The loops 8 hold the adjacent rectangles 9 in spaced relation to prevent the rectangles from pinching an occupant of the mattress. The top member which may be held to the springs by clips preferably has a binding 11 on its outer edge to protect the ends of the strips 6.

For sleeping in hot weather the mattress may be utilized with no covering whatever, the user lying directly on the top member 5. In this event, the openings between the strips making up the top member allow a circulation of air to contact directly with the user's body through the openings, thereby effectively cooling the occupant on the side in contact with the mattress. Moreover, the strips 6, if of metal, or any other suitable heat conducting material, will conduct heat rapidly away from the occupant's body, thereby even more effectively cooling the occupant. This conduction of heat away from the user and dissipation of heat from the mattress top is a result of the room temperature being lower than body temperature. Although it may appear that such a mattress top would be hard, it will be understood that as the size of the rectangular elements making up the top surface is diminished, the user

- will be so uniformly supported over the portions contacting with the mattress top that it will be far from uncomfortable to utilize the mattress with no padding on the top thereof. Moreover, 5 the strips 6 are relatively thin and also relatively narrow so that there are no appreciable sharp corners and the area of the openings in the top surface is relatively small.

To improve the appearance of the mattress the 10 construction above described may, if desired, have a covering 12, Fig. 5, of canvas, or other material applied to the bottom and a similar covering 13 applied to the side, this latter covering 13 preferably having relatively large openings 14, Fig. 5 15 for the circulation of air therethrough. The coverings may be secured to the mattress structure by any suitable means, as by sewing the coverings to parts of the mattress structure.

For hot weather use, where the occupant does 20 not wish to sleep directly on the top member, there may be applied to this top member a relatively thin fabric covering 15, Fig. 5, such as light weight sheeting, which preferably has releasable fastening means 16, of any conventional form, 25 attached to the edge thereof for engagement with cooperating fastening means 17 attached to the side wall covering. Any suitable releasable fastening means may be used; the purpose of the fastening means being to releasably secure the covering 15 in place on the top member. This covering 15 30 obviously should not cover the openings 14 as this would seriously decrease the cooling action resulting from air circulation.

In order that the mattress structure above 35 described may be utilized the entire year, the invention contemplates the use of a pad applied to the upper side of the top member. To this end a pad 18 corresponding in shape to the top member is laid thereon and this pad has releasable fastening 40 means 19 on the edges thereof, Fig. 6, adapted to cooperate with the fastening means 17 used in the summer for holding the fabric covering in place. Thus, during the colder months of the year the 45 mattress structure, with the pad thereon, may be used as a conventional mattress and gives the appearance in general of a conventional inner-

spring mattress. During the hot weather the pad will be removed and either no covering for the top member, or the thin fabric of Fig. 5, substituted.

From the foregoing it will be apparent that the 5 invention involves an open work top member for a mattress, preferably of heat conducting material which will accommodate itself to a user's body without buckling, and will remain flat when not in use. The particular arrangement provides a 10 mattress substantially equaling in comfort the conventional innerspring mattress, and which, with the pad of Fig. 6, may be a cold-weather mattress so that the structure can be used the 15 entire year.

I claim:

1. A mattress top comprising a multiplicity of relatively small substantially flat rectangular elements made up of interwoven strips of heat conducting material, said elements being closely 20 spaced from each other and all in substantially the same plane, and resilient means interconnecting said elements and allowing a relative movement therebetween.

2. A mattress top comprising a multiplicity of 25 relatively small substantially flat rectangular elements made up of interwoven strips of heat conducting material spaced from each other, said elements being closely spaced from each other and all in substantially the same plane, and resilient means in the form of depending loops 30 integral with the interwoven strips, said means interconnecting said elements and allowing a relative movement therebetween.

3. A mattress top comprising a multiplicity of 35 relatively small substantially flat rectangular elements, each made up of several strips of heat conducting material spaced laterally from each other, said elements being closely spaced from each other and all in substantially the same plane, and resilient means in the form of depending loops 40 integral with the strips, said last means providing an interconnection between adjacent rectangular elements and allowing a relative lateral or up and down movement therebetween. 45

ROBERT H. HAMBLIN.
